A FIRM.

DESIGN FOR A HANDLE FOR SPOONS, FORKS, OR SIMILAR ARTICLES.

SPECIFICATION forming part of Design No. 35,964, dated June 24, 1902.

Application filed May 31, 1902. Serial No. 109,801. Term of patent 7 years.

To all whom it may concern:

Be it known that I, ALBERT E. HATHAWAY, a citizen of the United States, residing at North Attleboro, in the county of Bristol and State of Massachusetts, have invented and produced a new and original Design for the Handle of a Spoon, Fork, or Similar Article, of which the following is a specification, reference being had to the accompanying drawings, forming part thereof.

Figure 1 is a view of the front or obverse side of the handle, showing my design; and Fig. 2 is a view of the rear or reverse side of the same. The handle is shown attached to the bowl of a spoon in solid lines, the tined blade of a fork being indicated in broken lines.

As shown in the drawings, the leading or material feature of my design consists of raised ribbon-like bands, presenting the appearance of grasses, dividing the handle into three panels and ornamenting the same. The upper end of the handle is ornamented with azalea flowers and leaves. The lower panel is ornamented with an azalea flower

and buds. On the obverse side the raised bands extend along the edges of the handle and curve inward under the floral decorations at the upper end of the blade of the handle. The lower part of the blade is ornamented by oppositely-disposed grasses forming flowing loops, interspersed with azalea buds and flowers. On the reverse side of the handle the ribbon-like bands extend along the margin of the handle and, curving inward, form three loops supporting the floral decoration on the upper end of the handle.

Having described my invention, what I claim as new, and desire to secure by Letters Patent, is—

The design for the handle of a spoon, fork, or similar article, as herein shown and described.

In testimony whereof I have signed my name to this specification in the presence of two subscribing witnesses.

ALBERT E. HATHAWAY.

Witnesses:

F. T. HANNIGAN,
GEO. H. MAINTIEN.
